CLAIM

The ornamental design for a shoe outsole, as shown and described.

DESCRIPTION

FIG. 1 is a bottom plan view of a shoe outsole showing my new design;

FIG. 2 is a cross-section taken generally along the line 2—2 of FIG. 1;

FIG. 3 is a cross-section taken generally along the line 3—3 of FIG. 1; and,

FIG. 4 is a cross-section taken generally along the line 4—4 of FIG. 1.

The cross-sectional Figures above illustrate the outsole only in the cross-sectional plane.
